BUILDING SCREEN WALL

Gordon J. Clauss, 2705 Katherine St., Fort Myers, Fla.

Filed Oct. 27, 1961, Ser. No. 67,290

Term of patent 14 years

(Cl. D18—2)

FIG. 1

FIG. 1 is a front elevational view of a building screen wall, embodying my new design;

FIG. 2 is a perspective view of one of the unitary blocks on a larger scale, shown in FIG. 1.

I claim:

The ornamental design for a building screen wall, as shown.
